UNITED STATES PATENT OFFICE

HARRY T. EISELE, OF WEST DOVER, OHIO

RATCHET GUIDE AND SUPPORT

Application filed April 24, 1931. Serial No. 532,663.

This invention relates to an improved ratchet guide and support and one object of the invention is to provide a device of this character by means of which a ratchet carrying a bit may be supported in an operative position for boring an opening through a joist and so guided that a straight opening may be bored through a joist at a desired angle.

10 Another object of the invention is to so mount the guide that when boring openings through a number of joists in a wall the openings may be formed in axial alinement with each other and thereby permit a pipe to extend in a straight line and have proper fit in all of the openings through which it passes.

Another object of the invention is to so construct the ratchet guide that it may be used in connection with pipes of various 20 standard diameters and to also permit the device when in use to serve not only as a device to support and guide a ratchet while boring a hole in a joist but also permitted to be employed as an indicator to form a mark upon 25 a side of a joist and indicate the proper location for an opening to be bored through the same.

Another object of the invention is to permit a pipe serving as a carrier for the support and guide to extend through openings already formed in two or more joists thereby insuring boring of an opening in another joist at the proper angle and also permitting the pipe to be moved longitudinally and 35 properly advance a bit as an opening is bored.

Another object of the invention is to not only permit a pipe to serve as a carrier for the ratchet guide and support but also serve 40 as a hand hold which may be grasped by a workman standing upon a ladder or similar support thereby making it easier for the workman to bore an opening at such a height that it could not be bored while standing 45 upon a floor of a room.

Another object of the invention is to provide a device of this character which is extremely simple in construction, strong and durable and capable of being manufactured 50 at a low cost.

The invention is illustrated in the accompanying drawing wherein:

Figure 1 is a view partially in section and partially in elevation showing the ratchet support engaged in a pipe to pass through 55 openings formed in a pair of joists.

Figure 2 is a view similar to Figure 1 showing the device moved into position to engage a joist and indicate the position at 60 which an opening is to be bored therein.

Figure 3 is a view showing a tool of the ratchet type and carrying a bit by means of which an opening has been formed through a joist.

Figure 4 is an enlarged view looking at 65 one end of the improved ratchet support and guide.

Figure 5 is a side elevation thereof.

Figure 6 is a view showing the improved ratchet guide and support partially in longitudinal section and partially in side elevation, and

Figure 7 is a sectional view taken along 70 longitudinally through one of the sleeves forming part of the improved device.

This improved ratchet support and guide is intended to support a tool holder 1 of the ratchet type having an operating handle 2 and adapted to carry a bit or auger 3 by means of which an opening 4 is to be formed 75 in a joist 5, which may extend vertically of the wall or serve as a ceiling beam. When erecting a building the wall joists or ceiling beams 5 are spaced transversely from each other and in order to support pipes forming part of the heating or plumbing system or as conduits for electric wires it is customary 80 to form openings through the joists.

The pipes should fit snugly in the openings 85 in order that they may be well supported and pipes used for hot water or steam heating should extend at an angle instead of horizontally. The openings formed in the joist should be in alinement with each other so that a pipe may be easily passed through 90 the openings.

The improved ratchet guide and support indicated in general by the numeral 6 has engagement with the tool or bit holder 1 as 95 shown in Figure 3 and is engaged in a pipe 100

7 which may be of any length desired but should be at least of sufficient length to engage through openings formed in two joists and project from the same as shown in Figure 1. This pipe will of course be of the same diameter as the pipe which is to be mounted in the openings formed through the joists. By this arrangement openings of the proper diameter to receive a pipe may 10 be formed in the joist and by moving the pipe longitudinally through the openings already formed a spur 8 at one end of the guide may be brought into contact with the next joist to be bored as shown in Figure 2 15 thereby accurately marking the joist so that an opening may be formed therein in axial alinement with openings already formed in other joists.

The guide or support has a shank 9 which 20 is circular in cross section and at one end of the guide is formed a squared end portion or head 10 from the outer end of which projects the spur 8 located centrally thereof. A collar 11 is formed about the guide between the shank 9 and the head 10. The shank of the guide is of a diameter permitting it to fit snugly within a pipe of the smallest diameter generally used and therefore when a small pipe is to be employed the 25 guide may be fitted into one end of a short length of pipe and the flange 11 will bear against the end of the pipe. After an opening has been bored in one joist a length of pipe which is quite short is engaged through 30 this opening and moves forwardly until the spur 8 bears against a side face of the next joist to be bored. This marks the position at which an opening is to be formed in the second joist. The pipe is then withdrawn 35 a sufficient distance to permit the ratchet wrench 1 to be engaged with the head 10 and bear against the shoulder 11 and the spur 12 of the bit or auger is engaged with the mark formed by the spur 8. The pipe is held by one hand in order to apply pressure 40 to urge the bit toward the joist to be bored while at the same time the handle 2 is actuated to rotate the bit and form an opening through the joist. After the second opening 45 is formed a longer pipe is used. This pipe should be of sufficient length to engage through the openings bored in the two joists and be moved forwardly a sufficient distance to mark the next joist without moving entirely out of the openings in the two joists 50 through which it extends. It will thus be seen that the pipe which serves as a carrier for the guide will be well supported in openings formed through two joists and will constitute a convenient hand hold for a workman standing upon a step-ladder or other support while boring an opening through a third joist. The fact that the pipe engages through two openings will also serve 55 to prevent it from having side play and mov-

ing out of its proper angle which may be either horizontal or at an incline.

When the tool holder and guide is used in connection with a pipe of a larger diameter it should still have snug fit within the pipe and be retained in axial alinement therewith and in order to do so there has been provided a number of sleeves 13 which fit about the shank 9 of the guide one within another as shown in Figure 6 and each sleeve is formed at its forward end with an outstanding annular flange 14 serving to limit sliding movement of the sleeve one within another in one direction and also serving to engage an end of a pipe.

It will be understood that each sleeve has an external diameter corresponding to the internal diameter of a pipe of a standard size and therefore by applying the proper number of sleeves about the shank they may serve as bushings to snugly fill the interior of the pipe and cause the tool guide to be disposed in axial alinement with the pipe. It will thus be seen that the device may be used in connection with pipes of any standard size and openings formed through joists which will be of the proper diameter to snugly receive a pipe and so alined with each other that the pipe will extend at the proper angle. It will also be noted that when this device is in use the bit may be held in engagement with a joist to be bored and proper pressure applied to feed the bit forwardly as the opening is bored.

From the foregoing description of the construction of my improved invention, the operation thereof and the method of applying the same to use will be readily understood. It will be seen that I have provided a simple, inexpensive and efficient means for carrying out the objects of the invention.

While I have particularly described the elements best adapted to perform the functions set forth, it is obvious that various changes in form, proportion and in the minor details of construction may be resorted to, without departing from the spirit or sacrificing any of the principles of the invention.

Having thus described the invention what is claimed is:

In a means for guiding and holding a ratchet tool, a plurality of telescoping sleeve members, each provided at its forward end with a peripheral flange adapted to abut the peripheral edge of the next encircling sleeve, said flanges being stepped with relation to one another when the sleeve members are assembled and limiting the movement of the respective sleeves in one direction, a cylindrical shank fitting snugly in the inner telescoping sleeve member provided with a squared tool engaging outer end portion adapted to project beyond the forward end of the last mentioned sleeve, said squared end portion terminating in a spur, and a circumferential flange formed integral with said shank at the

junction of the squared portion with the body
of said shank, said latter flange being adapted
to abut the forward peripheral edge of the
inner sleeve to limit movement of said shank
5 in one direction and also complete the stepped
sequence of the aforesaid flanges.

In testimony whereof I affix my signature.
HARRY T. EISELE.
